Primary Examiner — Marissa J. Cash*Assistant Examiner* — Kayla Marie Bennett(57) **CLAIM**

The ornamental design of a multitool as shown and described.

DESCRIPTION

The patent or application file contains at least one drawing executed in color. Copies of this patent or patent application publication with color drawing(s) will be provided by the Office upon request and payment of the necessary fee.

FIG. 1.1 is a top plan view of a multitool showing our new design;

FIG. 1.2 is a bottom plan view thereof;

FIG. 1.3 is a top perspective view thereof;

FIG. 1.4 is another top perspective view thereof;

FIG. 1.5 is another top perspective view thereof;

FIG. 1.6 is another top perspective view thereof.

1 Claim, 6 Drawing Sheets
(6 of 6 Drawing Sheet(s) Filed in Color)
